(57) **CLAIM**

The ornamental design for a display screen with animated user interface, as shown and described.

DESCRIPTION

FIG. 1 is a front view of a display screen with animated user interface showing the new design;

FIG. 2 is the second image thereof;
FIG. 3 is the third image thereof;
FIG. 4 is the fourth image thereof;
FIG. 5 is the fifth image thereof;
FIG. 6 is the sixth image thereof;
FIG. 7 is the seventh image thereof;
FIG. 8 is the eighth image thereof;
FIG. 9 is the ninth image thereof;
FIG. 10 is the tenth image thereof;
FIG. 11 is the eleventh image thereof;
FIG. 12 is the twelfth image thereof;
FIG. 13 is the thirteenth image thereof; and
FIG. 14 is the first image of a second embodiment thereof;
FIG. 15 is the second image thereof;
FIG. 16 is the third image thereof;
FIG. 17 is the fourth image thereof;
FIG. 18 is the fifth image thereof;

FIG. 19 is the sixth image thereof;
FIG. 20 is the seventh image thereof;
FIG. 21 is the eighth image thereof;
FIG. 22 is the ninth image thereof;
FIG. 23 is the tenth image thereof;
FIG. 24 is the eleventh image thereof;
FIG. 25 is the twelfth image thereof; and,
FIG. 26 is the thirteenth image thereof.

The broken line showing of the display screen in both embodiments and of the numbers in the second embodiment is for environmental purposes only and forms no part of the claimed design. The appearance of the image transitions sequentially between the images shown in FIGS. 1-13 and FIGS. 14-26. The process or period in which an image transitions to another forms no part of the claimed design.
